[57] CLAIM

The ornamental design for a hoe plow blade, substantially as shown and described.

DESCRIPTION

FIG. 1 is a perspective view of a hoe plow blade showing my new design;

FIG. 2 is a top plan view thereof;

FIG. 3 is a right hand elevational view thereof;

FIG. 4 is a left hand elevational view thereof;

FIG. 5 is a front elevational view thereof;

FIG. 6 is a rear elevational view thereof; and,

FIG. 7 is a bottom plan view thereof.

The broken lines representing the handle member are shown for illustrative purposes only.
